Primary Examiner—Ian Simmons*(74) Attorney, Agent, or Firm*—Nixon & Vanderhye P.C.**(57) CLAIM**

The ornamental design for a portion of a full face mask, as shown and described.

DESCRIPTION

FIG. 1 is an isometric view of a full-face mask according to a first embodiment having a three-hole vent and a low profile connector; and,

FIG. 2 is an isometric view of a full-face mask according to a second embodiment having a three-hole vent and a high-profile connector.

The broken line showing in the FIGS. 1 and 2 are for illustrative purposes only and forms no part of the claimed design.

1 Claim, 2 Drawing SheetsFIG. 1

FIG. 2
